UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A BASE FOR LAMP-FOUNTS.

SPECIFICATION forming part of Design No. 24,132, dated March 19, 1895.

Application filed February 18, 1895. Serial No. 538,900. Term of patent 3½ years.

To all whom it may concern:

Be it known that I, ALBERT PATITZ, of Meriden, in the county of New Haven and State of Connecticut, have invented a new Design for a Base for Lamp-Founts, (Case A); and I do hereby declare the following, when taken in connection with the accompanying drawings and the letters of reference marked thereon, to be a full, clear, and exact description of the same, and which said drawings constitute part of this specification, and represent, in—

Figure 1, a side view of a base for lamp-founts embodying my design; Fig. 2, a top view of the same.

This invention relates to a design for a base for a lamp-fount, and the design consists in the configuration and ornamentation as shown in the accompanying illustrations.

The design consists of a square base, having four legs A, terminating in upwardly turned scroll feet B, the legs surrounded or bordered by scroll and leaf ornamentations C, which ex-

tend upward and surround prominent, plain ornaments D projecting considerably from the general surface of the base, and forming the corners thereof. From these prominent projecting ornaments D, rise foliations E, curving abruptly inward and slightly upward, forming the square shape of the base. The spaces between the legs A and projecting ornaments D, are filled by reversely curved foliated scrolls F, curving inward and upward, all as shown in the accompanying illustrations.

I claim—

The design for a lamp-fount base as herein shown and described.

In testimony whereof I have signed this specification in the presence of two subscribing witnesses.

ALBERT PATITZ.
